UNITED STATES PATENT OFFICE.

GEORGE T. BOND, OF HUNTINGTON, WEST VIRGINIA.

PROCESS OF MAKING BRAKE-SHOES AND PRODUCT THEREOF.

1,227,376.

Specification of Letters Patent.

Patented May 22, 1917.

Application filed February 15, 1917. Serial No. 148,870.

To all whom it may concern:

Be it known that I, GEORGE T. BOND, a citizen of the United States, residing at Huntington, in the county of Cabell and 5 State of West Virginia, have invented a certain new and useful Process of Making Brake-Shoes and Product Thereof, of which the following is a specification, reference being had therein to the accompanying 10 drawing.

This invention relates to the use of brake-shoes that have become worn in service in the making of new shoes, and more particularly the invention pertains to such use of 15 worn shoes in substantially the form in which they are taken from the brake-heads, whereby the necessity of melting the worn shoes for recovery of the metal thereof is avoided.

It is of common practice to remove shoes 20 from service when only slightly more than one-half the metal of the body thereof is worn away and to remelt them. This necessitates, not only the expense of remelting 25 and remolding, but it also involves the considerable expense of labor due to more frequent removals, of frequent handling in shipping from place of removal to place of melting, of accounting, and of various 30 other items incident to a curtailed service.

In order to avoid these disadvantages, and in order to make use of worn shoes without substantial or expensive change in their 35 form, this invention provides a process, for incorporating the worn shoes into new ones, that can be practised without difficulty in car-repair plants with facilities that easily can be installed and operated therein, and the invention also is directed to the 40 shoe so produced.

When read in connection with the description herein, the features of the invention will be apparent from the accompanying drawing, forming part thereof, which 45 is illustrative of the steps of the process and of the article produced.

While the disclosures herein now are considered to exemplify preferable embodiments of the invention, it is to be understood that it is not the intention to be limited necessarily thereto in interpretation of the claims, as departures therefrom within the limits of the claims can be made without departing from the nature and spirit 50 of the invention.

Like reference-characters refer to corre-

sponding parts in the views of the drawings, of which—

Figure 1 is a side elevation of a partially-worn brake-shoe in position to be pressed 60 against the face of, and into association with, a new shoe;

Fig. 2 is a side elevation, partly in section, of a new and old shoe pressed into interlocked association and constituting a 65 unitary article;

Fig. 3 is a view of the back or keeper side of a brake-shoe; and

Fig. 4 is a view of the front or wearing side of a brake-shoe.

Referring more particularly to the drawing, A designates a partially-worn brake-shoe, the original contour of the wearing side of which is indicated by a dotted line 70 A', and B an unworn shoe.

Shoes of the type of that at the left of Fig. 1 are among those extensively in use on railway-cars. Such a shoe, as well as that at the right of Figs. 1 and 2, includes a body portion 5, which has a continuously- 80 curved wearing-surface conforming to the periphery of the surface of the wheel against which it contacts, as indicated by the dotted line A', and a rear face substantially parallel therewith. The body portion 85 may be formed partly or entirely of chilled metal, it may have inserts of any suitable material to increase the wearing and friction qualities as commonly practised in the art, or it may be of ordinary gray or white cast iron, at the discretion 90 of the maker and user to meet the particular demands of the service to which it is to be put.

The shoe has one or more keepers 6, projecting backwardly from the side opposite to the wearing-face, each to seat in a correspondingly-shaped recess in a brake-head and thereby to hold the shoe in place thereon. The keepers are of malleable sheet steel, 100 they are formed with legs 6^a and a connecting-piece 6^b, and they are provided with openings 7 formed through the legs and disposed in longitudinal series with respect to the shoe for reception of a securing-key 105 (not shown) whereby the shoe is prevented from becoming displaced from the brake-head. In the type shown the keepers are formed integrally of a back 8 by bending from sheet-metal stock at intervals to dovetail shape, they extend transversely of the shoe, and in manufacture the shoe-body is 110

cast to the back. The metal, during the process of molding, flows through openings 9 in the back, whereby connection of the parts is effected and reliably maintained. 5 Moreover, in order to contribute to a reliable maintenance of connection of the parts, the mold is so shaped that the body metal extends slightly beyond the rear contour-line of the body against the inside of 10 the legs of the keepers (as indicated at 5^a), the surface between the legs lying in a curve the reverse of that of the contour of the body (as indicated at 5^b). The keyways 7 and securing-openings 9 preferably are 15 formed in the stock before bending.

In order that a shoe, when it has become worn to such an extent that it is advisable to withdraw it from service (say to the place indicated by the full line A" in Fig. 20 1), may be embodied intact as a wearing member and as a part of the wearing portion of another shoe, the invention provides for employment of the keepers that have been used to hold the shoe on a brake-head 25 to hold the worn shoe on the other shoe.

For this purpose, the unworn shoe is formed in its body with one or more recesses or mortises 10 extending transversely thereof and opening to the wearing-face, 30 the number of such recesses being the same as of the keepers of the worn shoe, they are substantially the same width as these keepers, and they are arranged to have the keepers pressed into them, whereby the 35 worn shoe is incorporated as a part of the unworn one. Usually the keepers are of the same width as the shoe-body, and, therefore, the mortises extend entirely across the shoe-body and are open at the sides thereof. The 40 end walls of each mortise overhang (as indicated at 10^a), and the bottom of the mortise bulges or curves outwardly between the ends (as indicated at 10^b). Thus there is provided for every keeper of the worn shoe 45 a mortise of somewhat dovetail shape, having comparatively deep pockets (as indicated at 10^c) under its overhanging walls. The depth of the recess at the center is the same as or slightly greater than the thickness 50 of the material of the keepers, and the pockets are of sufficient extent and so located as to receive a bend and two thicknesses of the material when bent back upon itself.

55 In order to secure a worn brake-shoe to an unworn one and thus to obtain a unitary article in which the unworn part of the used shoe constitutes a wearing member that is held against the wearing-face of the unworn shoe and is coextensive therewith and is employed until completely worn away, the two shoes are placed in the relative positions shown by Fig. 1 in a press or other suitable machine having suitable holding-dies and 60 a ram. The keepers are held in alinement

with and extend toward the mortises of the unused shoe, which latter is held in fixed position. The ram is caused to press against the concave wearing-face of the used shoe (A) and that shoe thus forced toward the 70 unused shoe (B). The ram continuing to advance, the malleable keepers of the worn shoe are forced into, and bent to conform to the shape of, the recesses or mortises 10, which latter are just sufficiently extensive to 75 accommodate the material of the keepers when bent to the shape and folded over into the pockets thereof. The metal of the shoe-body projecting between the legs of the keepers is accommodated by the mortises, this metal resting against what was the part that connected the legs of the keepers. Thus the keepers are shaped into tenons in the mortises and conform to the shape of and tightly fit in the mortises. 80

85 By the time the keepers are forced to shape in the mortises, the rear face of the worn shoe is brought against the contact face of the unworn shoe. The abutting faces of the two shoes being of the same 90 contour, when pressed together they contact practically at all places between the mortises and such contact is reliably maintained by the pressed-in keepers until the old shoe is worn away, after which further wear is 95 taken by the body of the newer shoe, which, after being worn to such an extent that it is advisable to withdraw it from service, may be attached to a still newer shoe in the manner hereinbefore described. After the 100 two shoes are pressed together, the ram is withdrawn and the article produced is removed from the press, when it is ready for use.

In a shoe having a plurality of keepers— 105 for example three in the type shown—the keyways 7 through the legs of the end keepers usually extend into the material connecting the legs (as indicated at 6^c), for it is advisable to make the end keyways larger 110 to facilitate insertion and removal of the securing-key, because such keys may not always conform exactly to the curvature of the series of keyways. Thus, when the end keepers are pressed into the mortises 10, a 115 keyway-opening is at the bend in each pocket of the mortise and there constitutes a recess or seat. In order to prevent lateral displacement of the two shoes after being pressed together, an abutment 10^a, formed 120 integrally with the shoe-body, extends across the pockets in a position to be received by the seat or recess afforded at the bend by what was the keyway-opening.

Having thus described my invention, what 125 I claim as new, and desire to secure by Letters Patent, is—

1. A process of forming brake-shoes that includes the pressing of the rear face of a brake-shoe having a keeper extending there- 130

from into abutment with the contact-face of another brake-shoe having a mortise opening to said face and at the same time by the same action pressing said keeper 5 into and causing it to conform to said mortise.

2. A process of forming brake-shoes that includes the pressing of the rear face of a brake-shoe having malleable keepers extending therefrom into abutment with the contacting of another brake-shoe having mortises disposed in the same relative positions as said keepers, and by the same action pressing the keepers into and causing them to conform to said mortises.

3. A process of forming brake-shoes that includes the formation of a shoe-body with a mortise opening to the contact face thereof, and thereafter taking a brake-shoe having a rearwardly-extending malleable keeper and pressing the rear face of said shoe into abutment with the contact face of said body and by the same action pressing said keeper into and causing it to conform to said mortise.

4. A process of forming brake-shoes that includes placing a shoe-body having a mortise opening to the contact face thereof in fixed position in a press, placing a brake-shoe having a keeper on a ram of the press with its keeper in alinement with and extending toward said mortise, and then causing said ram to press said brake-shoe into abutment with said body and thereby pressing the keeper into and causing it to conform to said mortise.

5. A process of forming brake-shoes that includes the pressing of the rear face of a

brake-shoe having a fixed bendable keeper extending therefrom into abutment with the contact face of another brake-shoe having a mortise of less depth than the keeper opening to said face, and at the same time by the same action pressing and bending said keeper into and thereby causing it to conform approximately to the shape of said mortise.

6. A brake-shoe comprising a body having a transverse mortise opening to the contact-face thereof, said mortise having at each end an overhanging wall and a pocket inside of said wall and an abutment extending across said pocket, a wearing member abutting said contact face, and a tenon on said wearing member interlocked in said mortise and having a seat in which said abutment is disposed.

7. The combination of a brake-shoe body having a transverse mortise opening to the contact face thereof, and another brake-shoe body abutting said contact face and having as a permanent part thereof a malleable keeper pressed into said mortise whereby said bodies are held together.

8. The combination of a brake-shoe body having a mortise opening to the contact face thereof, and another brake-shoe body abutting said contact face and having fixed thereto a malleable keeper pressed and deformed into and thereby conforming approximately to the shape of said mortise, whereby said bodies are held together.

In witness whereof, I have affixed my signature.

GEORGE T. BOND.
